UNITED STATES PATENT OFFICE.

GEORGE I. ALLEN, OF WILSON, NORTH CAROLINA.

SMOKER'S DEVICE.

Application filed March 21, 1924. Serial No. 700,932.

To all whom it may concern:

Be it known that I, GEORGE I. ALLEN, a citizen of the United States, residing at Wilson, in the county of Wilson and State of North Carolina, have invented certain new and useful Improvements in Smokers' Devices, of which the following is a specification.

My invention relates to a device to be used 10 by smokers.

An important object of the invention is to provide a device of the above mentioned character, provided with means for holding a cigar or cigarette, means for receiving the 15 ashes, and means for holding a box of matches.

A further object of the invention is to provide a device of the above mentioned character, having means whereby it may be readily 20 attached to a part of a desk, table or the like.

A further object of the invention is to provide a device of the above mentioned character, so constructed that the same may 25 be stamped from a single sheet of metal or the like, whereby it may be produced quickly and cheaply.

A further object of the invention is to provide a device of the above mentioned 30 character having means for holding an advertising display.

Other objects and advantages of the invention will be apparent during the course of the following description.

35 In the accompanying drawings forming a part of this specification and in which like numerals are employed to designate like parts throughout the same,

Figure 1 is a perspective view of a device 40 embodying my invention,

Figure 2 is an elevation of the rear end of the device,

Figure 3 is a plan view of a blank from which the device is formed,

45 Figure 4 is a perspective view of a device embodying a second form of the invention.

Figure 5 is a plan view of the blank, parts broken away, from which the second form of the device is made,

50 Figure 6 is a perspective view of a device embodying a third form of the invention, and,

Figure 7 is a plan view of the blank from which the third form of the device is produced, parts being broken away,

55 Figure 8 is a side elevation of the same

device shown in Figure 1, showing the same applied to a desk in a different manner.

Attention is first called to Figures 1 to 3 inclusive, wherein is illustrated the first 60 form of the invention. In Figure 3, the numeral 10 designates a blank, which is stamped from a single sheet of metal, card board, or any other suitable material. This integral blank embodies a bottom portion 65 11, the front end of which is preferably rounded, as indicated at 12. The numeral 13 designates a front portion, formed integral with the body portion 11 and foldable thereon upon a line 14. The bottom 70 portion 11 is preferably provided with slots 15, for the reception of tongues 16 integral with the front portion 13. The bottom portion 11 is also provided with forwardly extending tongues 17, for a purpose to be described. Formed integral with the ends of the bottom portion 11 and foldable thereon upon lines 18, are end portions 19, provided at their forward ends with slots 20, for the 75 reception of tongues 21, carried by the front portion 13, as shown. Formed integral with the bottom portion 11 is a back portion 22, foldable thereon upon the lines 23. This back portion is provided at its ends with tongues 24, to enter slots 25 formed 80 in the end portions 19. As clearly shown in Figure 1, the front portion 14, end portions 19, and back portion 22 are bent upwardly with respect to the bottom portion 11 and are disposed at a right angle thereto, the 85 several portions being secured together by means of the tongues formed thereon, which are inserted through the corresponding slots and then bent back. These parts thus assembled produce an ash receiving tray or 90 receptacle 26.

The end portions 19 carry tongues or projections 27, which may be bent upon lines 28, and these tongues project forwardly beyond the ends of the front portion 13, and are adapted to engage over the end of an advertising card or display 29 which may rest upon the tongues 17 which are preferably bent upwardly.

Formed integral with the back portion 22, 105 and foldable upon a transverse line 30, is a support or clamp portion 31, having extensions 32, foldable upwardly upon lines 33. The extension 32 to the right is equipped with tongues 34. The extension 32 to the left is integral with a cigar or cigarette holding tray section 35, foldable upon line 110

36. This last named section is foldable at its end upon a line 37, producing an extension 38, having slots 39, to receive the tongues 34. The section 35 is transversely 5 corrugated providing depressions 40', extending longitudinally of the device, for holding cigars or cigarettes. As clearly shown in Figure 1, the back portion 22 projects above the ends 19 of the receptacle, and 10 the support portion 31 is horizontally arranged at a right angle to this back portion. The tray portion 35 extends above the clamp portion 31, in parallel relation thereto, with the extensions 32 vertically arranged, and the extension 38 bent downwardly to engage upon the outer side of the extension 32 to the left, with the tongues 34 entering the slots 39, which tongues are subsequently bent back. The cigar or cigarette 15 tray portion is therefore arranged at the rear end of the ash receptacle so that the ashes may be readily caught within such receptacle.

The back portion 22 carries strips 40, at 25 the ends thereof which are integral with the same, such strips being foldable upon lines 41. These strips are folded inwardly upon the rear face of the back portion 22, and may be held in contact therewith by tongues 30 42 stamped from the back portion, which tongues are passed through slots 43, and then bent back. The strips 40 are also foldable upon transverse lines 44, to provide 35 knuckles 45, disposed at a right angle to the back portion 22, and apertured to pivotally receive the arm 46 of a clamp or clamping frame 47, which is shown as rectangular. A torsional coil spring 48 surrounds the arm 46, with one end thereof engaging the clamp 40 47 and the other end the bottom portion 11. It is thus seen that the support or clamp portion 31 may be arranged upon the top of a portion of a desk, with the spring clamp 47 beneath such portion, thereby 45 securely holding the device in place. It is obvious that the device may be mounted upon any other suitable object, such as a table, chair or the like.

The numeral 49 designates a portion, integral with the support or clamp portion 31, and foldable at a right angle thereto, upon the line 50. The portion 41 is foldable upon lines 51, producing a horizontal intermediate portion 52 and a depending outer side or 55 jaw 53 arranged opposite the inner jaw 54. The top portion 52 has an opening 55 to receive the lower end of a box of matches. As clearly shown in Figure 1, the portion 49, when folded or bent produces an inverted U-shaped member, projecting above the tray 40. When the device is applied to the top of a portion of a desk or the like, as illustrated in Figure 8, the member 56 receives within its opening 55 a box of matches. It may be desired to apply the

device to the drawer of a desk or the like, in which event the member 56 is inserted over the upper edge of the front of the drawer. The drawer may be closed without removing the device.

In Figures 4 and 5 I have illustrated a slight modification of the device. All parts of the device are identical with that of the first form of the device, up to the portion 49, Figure 3, which portion is omitted. In 70 Figures 4 and 5 a transverse strip 57 is formed integral with the portion 31, at its center, as indicated at 58, with slits 59 separating the outer portions of this strip from the portion 10. The ends of the strip 57 are bent upwardly upon lines 60 forming vertical arms 61 which are bent upon lines 62, forming horizontal extensions 63 which may be suitably secured together. These parts thus bent form a rectangular frame over 75 which the outer section of the match box may be inserted. The same spring actuated clamp 47 is of course employed.

In Figures 6 and 7 I have illustrated a third modification of the device. This device is identical with the first form of the invention, as shown in Figure 3, up to the portion 31, and this portion with all elements carried thereby are omitted. The back portion 22 has an upper extension portion 65 formed integral therewith, and this extension portion is provided at its upper end with a lip 66, foldable downwardly upon a line 67, to occupy a position at the rear of the same. This lip is provided with a key 90 hole slot 68, for the receptacle of a tack or the like from which the device is suspended. Formed integral with the portion 65 are wing portions 69, foldable in a forwardly direction upon lines 70, and these wing portions are foldable upon lines 71 providing side members 72 of a match box holding cage. The sides 72 are foldable upon lines 73 providing flanges 74. The sides 72 have openings 75 through which a match may 95 be struck. Support flanges 76 are bent upon the lower ends of the sides 72. It is obvious 100 that a box of matches is held within the cage between the sides 72.

In view of the foregoing description it is 115 thought that the use of the devices is obvious, and no further description is deemed obvious.

While I have illustrated the several parts of the device as secured together by tongues and slots, the invention is not necessarily restricted to this manner of connection, as other means may be employed, such as solder, or clamp joints.

It is to be understood that the forms of 120 my invention herewith shown and described are to be taken as preferred examples of the same, and that various changes in the shape, size, and arrangement of parts, may be resorted to, without departing from the spirit 125 130 134

of my invention or the scope of the subjoined claims.

Having thus described my invention, I claim:

5. 1. A smoker's device formed from an integral blank, said blank including a receptacle portion, said receptacle portion comprising a bottom portion, a front portion foldable upwardly upon the bottom portion, 10 a back portion foldable upwardly upon the bottom portion, end portions foldable upwardly upon the bottom portion, said portions having interfitting tongues and grooves whereby they are retained in the assembled 15 position, the end portions having forwardly extending tongues arranged in close relation to the outer surface of the front portion and also adapted for receiving and holding the ends of an advertising card, and means for 20 securing the device upon a support.

2. A smoker's device formed from an integral blank, said blank including a receptacle portion, said receptacle portion comprising a bottom portion provided at its forward edges with tongues and having slots near such forward edge, a front portion integral with the forward edge of the bottom portion and foldable upwardly upon the same and provided upon its inner edge with 25 tongues to enter the slots in the bottom portion, said front portion having tongues at its ends, end portions foldable upwardly upon the bottom portion and provided at its rear edges with slots and having forwardly projecting tongues at its forward edge and slots spaced inwardly from the free ends of the tongues, the last named slots being adapted for the separation of the tongues formed upon the ends of the front portion, the 30 tongues upon the end portions being adapted to overlap the outer side of the front portion in close relation and also to receive the ends of an advertising card, the tongues upon the forward edge of the bottom portion being bent upwardly in advance of the front portion in close relation thereto and also adapted to support such card, the back portion foldable upwardly upon the said portion and provided with tongues to enter 35 the slots at the rear edges of the end portions, and means for securing the device to a support.

3. A smoker's device, comprising an ash receiving receptacle, a clamp portion carried by the receptacle and adapted to engage over a supporting object, said clamp portion having means for holding a cigar or cigarette, a spring actuated clamp member connected with the receptacle beneath the clamp portion, and an inverted U-shaped member carried by the free end of the clamp portion and adapted to engage over the edge of a drawer or the like.

4. A smoker's device, comprising a receptacle having a rear wall, a rearwardly extend-

ing support portion integral with the rear wall and bent at a right angle thereto, a tray portion integral with the support portion and bent above and across the same and being corrugated longitudinally of the device, and means to secure the support portion to a supporting object. 70

5. A smoker's device comprising an ash receiving receptacle, including a bottom portion, a front portion integral with the bottom portion and foldable upwardly thereon, end portions integral with the bottom portion and foldable upwardly thereon, said end portions having tongues extending forwardly beyond the same and the ends of the front portion for engaging the ends of an advertising display arranged upon the front of said front portion, a back portion foldable upwardly upon the bottom portion, and means for securing the assembled portions 85 together. 75

6. A smoker's device formed from an integral blank, said blank including a receptacle portion, said receptacle portion comprising a bottom portion, a front portion foldable upwardly upon the bottom portion, end portions foldable upwardly upon the bottom portions, and a back portion foldable upwardly upon the bottom portion, means for securing said portions together in the assembled folded position, extensions carried by the ends of the back portions and foldable upon the rear side thereof and carrying knuckles and having means for securing the same in place, a clamping element pivoted to the knuckles, a spring to move the clamping element upwardly, a support portion integral with the back portion of the receptacle and foldable at substantially a right angle to the same, said support portion carrying a laterally extending tray forming portions foldable over the top of the support portion and attached thereto at its free end, said tray portion being corrugated for the reception of cigars, 100 cigarettes and the like and to strengthen the same, and an inverted U-shaped member bent upwardly from the rear end of the support portion and adapted to engage over the end of a drawer or the like. 105

7. A smoker's device formed from an integral blank, said blank including a receptacle portion, said receptacle portion comprising a bottom portion, a front portion foldable upwardly upon the same, end portions foldable upwardly upon the bottom portions, a back portion foldable upwardly upon the bottom portion, means for securing said portions together in the folded assembled position, a support portion bent at substantially a right angle to the back portion and carrying a laterally extending tray portion which is foldable over the top of said support portion and connected at its free end with said support portion, said tray 110 115 120 125 130

portion being corrugated to strengthen the same, and an inverted U-shaped clamp foldable at substantially a right angle to the support portion and adapted to engage over 5 the upper end of a drawer or the like.

8. A smoker's device formed from an integral blank, said blank including a receptacle portion, said receptacle portion comprising a bottom portion, a front portion 10 foldable upwardly upon the same, end portions foldable upwardly upon the bottom portion, a back portion foldable upwardly

upon the bottom portion, means for securing said portions together in the folded assembled position, a support portion bent at substantially a right angle to the back portion and carrying a laterally extending tray portion which is foldable over the top of the said support portion and connected at its free end with said support portion, said tray 20 portion being corrugated to strengthen the same.

In testimony whereof I affix my signature.
GEORGE I. ALLEN.
